ABSTRACT OF THE DISCLOSURE

Ski binding adjustment means for the threaded adjusting of the position of a binding component relative to another, where a threaded spindle is journalled in one of the parts to be mutually adjusted in the longitudinal direction and where a nut threadedly mounted on the spindle has a catch that projects from this part and into a recess or opening of the counter part.

BACKGROUND OF THE INVENTION

The invention relates to ski bindings. More particularly, the invention relates to an arrangement for ski bindings for threadedly adjusting the relative position of the binding component to another component, such as the sole or base plate or the like. Bindings are known having a threaded spindle that is provided with a left and a right hand thread and which with each of these threads engages a corresponding threaded bore in the ski or binding parts that are adjustable relative to one another. In addition an adjusting nut and a counter nut are provided. The manufacture of this type of adjusting device, including the left hand and right hand threads and the required threaded bores in the parts to be adjusted, is relatively expensive. Moreover, such threaded bores can only be provided in correspondingly strong and wear resistant parts. For example, it would not be possible to use thin plastic walls or strips for this purpose because the thread portion would tear or split. Also the installation or assembly of such an adjusting device is relatively complicated. In addition, there are the shortcomings that the adjusting range cannot be greater than the length of the threads and that the adjusting spindle projects rearwardly from the base plate.

It is an object of the invention to provide a threaded adjusting means that is simple in construction and readily assembled while avoiding the aforementioned shortcomings, and where in addition it is also possible with simple means to considerably widen the adjusting range.

Accordingly, the invention resides primarily in that the threaded spindle is journalled in one of the parts to be adjusted relative to one another where it is secured against longitudinal displacement, and that a nut threadedly mounted upon the spindle has a catch that extends from this part and engages recesses or the like in this counter part. Several advantages are provided by this. The threaded spindle may in any desired and simple manner be held on the associated component. For example, in accordance with the preferred embodiment of the invention it is possible to place it or press it into the slotted or fork-shaped bearings of this part. The necessary height of such a support or bearing is relatively small, so that the spindle can be readily placed in the lateral borders or strips of a sole or base plate while the catch projects upwardly out of this plate. As a matter of course the spindle in accordance with the invention may also be journalled in the particular component of the binding which is to be adjusted (front jaws,

2

heel binding, and the like) and engage with the catch a corresponding recess of the sole plate or the like.

The threaded spindle always maintains the same position relative to that part in which it is inserted. Suitably the arrangement may be such that only its screw head extends from this part while the threaded shaft is arranged within the part but is protected against ice accumulation and damage. Besides that, the danger is thus avoided that the skier can injure himself on the setting screw.

The spindle, the threaded nut and their catch are simple and can be produced at very low cost on automatic lathes. The manufacture of the journals also requires no considerable costs in the particular component. It is of particular advantage that these bearings can be applied or installed subsequently on existing base plates or binding parts without it being necessary to correspondingly change existing tools.

It is furthermore made possible in accordance with the invention to considerably widen the adjusting range. For this purpose one or several cut-outs or recesses are provided in the part at distances behind one another in the direction of adjustment while preferably one distance is equal to the adjusting range of the spindle. By introducing the catcher into the particular recess a coarse adjustment can be had, and by turning the screw the corresponding fine adjustment is obtained.

BRIEF DESCRIPTION OF THE DRAWINGS

Further advantages and features of the invention will become apparent from the following description with reference to the embodiments illustrated in the drawings, in which

FIG. 1 is a bottom view of a sole or base plate provided with the threaded adjusting means in accordance with the invention,

FIG. 2 is a section taken along line II—II in FIG. 1,

FIG. 3 is a perspective view of the device in accordance with FIGS. 1 and 2,

FIG. 4 illustrates parts of a further embodiment of the invention with a damping spring,

FIG. 5 is a side view of a further modification of the invention,

FIG. 6 is a sole plate which may be associated with the embodiment of FIG. 5 and where several recesses are provided.

DESCRIPTION OF THE INVENTION

In the embodiment in accordance with FIGS. 1 to 3 the threaded spindle 1 is retained in a base or sole plate 2 or the like, which could also be a heel mounting plate, while the catcher 3 of the threaded nut 4 engages a recess 5 of the binding component 6 which is to be adjusted. The binding part 6 may be a safety head, an automatic heel binding or the like. Besides, the threaded nut may have a shoulder 4' on the side which carries the catch, upon which the counter part 2 can rest with relative safety against tilting.

In accordance with a particularly simple and practical embodiment of the invention the threaded spindle is laid into a slot or forked bearing of the particular part. This journal construction is provided here at 7 in the border 2' of the plate 2 and is open at the bottom. An arrangement of such type that the threaded spindle can be pressed into this bearing with a snapping or clamping effect and which is self-supporting is advisable. For this purpose it is advantageous if the component provided with this bearing or journal consists of a somewhat resilient plastic. The other end of the spindle 1 suitably is also journalled and held, for example, in a forked portion 7' of the strip 2''. The catch 3 and the recess 5 may be optionally formed. If desired the threaded spindle may be covered by the

plate 2 (see FIGS. 1-3) which has a slot 8 for passage of the catch 3 that extends over the range of adjustment.

As a safeguard against longitudinal displacement of the spindle one or several flanges or shoulders 9 may be provided. In the example of FIGS. 1-3 this arrangement is of a particularly simple type in that the collar 9 is at a distance from the screw head 10 which corresponds to the thickness of the wall 2' or of the corresponding strip of the plate 2 in which the spindle is placed. The setting of the screw is effected by inserting a screwdriver or a coin into the slot of the screw head 10. Instead the setting could also be effected by means of a knurled knob that can be manipulated by hand.

FIG. 4 indicates that the spindle 1 can be supported for longitudinal displacement over a limited path in the direction S against the effect of a spring 11. This spring, however, serves the purpose of compensating for the thrust that arises as the boot is inserted or pressed into the binding. This is necessary particularly when the safety device, for example a heel release, is adjusted too tightly and thereby too large a force of compression arises between the shoe and the binding. Suitably the spring 11 is provided between a collar 9' of the spring and a counter part of the particular component, for example a wall or a strip 2'' of the sole plate or the like. It is understood that the spring 11 may also be in the form of a nest of spring washers or as a flat spring.

As already explained, the threaded spindle may also be on the part which is to be adjusted (safety head, automatic heel binding), while the counter part which has the recess is constituted by the base plate, sole plate, mounting plate, or the like. It is therefore within the scope of the invention that the means described in the embodiments in connection with one part may also be provided in the reverse arrangement in the corresponding counter part. Thus FIG. 5 illustrates schematically the heel retaining binding 13 which holds the heel 12 of a ski boot and in which a threaded spindle 14 is located. This spindle supports a threaded nut 15 having a catch 15' which engages a corresponding recess 16 of the base or sole plate 17.

FIG. 6 shows the arrangement of several apertures 18 already mentioned, which are disposed at distances from one another in the direction of the adjustment, where a space "a" corresponds suitably to the adjustment range of the associated threaded spindle. As mentioned above, it would, of course, also be possible in the embodiments in accordance with FIGS. 1-3 and 4 to provide several apertures in the binding part 6 at such distances behind one another. Thus, if a range for fine adjustment is no longer sufficient for obtaining the desired position, the

catch is simply removed from the aperture or recess and is placed into the next recess.

Having now described my invention with reference to the embodiments illustrated in the drawings, what I desire to protect by Letters Patent of the United States is set forth in the appended claims.

I claim:

1. Ski binding mechanism for the threaded adjustment of the position of an automatic heel binding component relative to another component, for example the base plate, comprising a threaded spindle journalled in one of said components, holding means in said one component securing said spindle against longitudinal displacement relative to said plate, and a threaded nut on said spindle having a catch projecting therefrom as a unitary member, the other said component having a recessed configuration for interengagement with said catch, said catch extending into said configuration, said holding means being defined by a forked bearing in a portion projecting from the surface of one said component adapted to receive said spindle with a clamping effect in response to pressure and defining a shoulder, and by a pair of configurations extending radially from said spindle on opposite sides of said shoulder.

2. Ski binding mechanism in accordance with claim 1, where one configuration of said pair is in the form of a collar and the other is a screw head.

3. Mechanism in accordance with claim 1, where said component on which said spindle is journalled is provided with a cover plate, said plate defining a slot through which said catch projects, and said slot extends over the adjustment range of said spindle.

4. Mechanism in accordance with claim 1, where said configurations extending radially from said spindle are spaced at a predetermined distance from one another and a biasing spring is disposed intermediate one said configuration and said shoulder.
